UNITED STATES PATENT OFFICE.

JOHN B. HUDDLE, OF EAST ST. LOUIS, ILLINOIS.

COIN-RECEPTACLE.

1,287,025.

Specification of Letters Patent. Patented Dec. 10, 1918.

Application filed September 14, 1916. Serial No. 120,024.

To all whom it may concern:

Be it known that I, JOHN B. HUDDLE, a citizen of the United States, residing at the city of East St. Louis, county of St. Clair, 5 and State of Illinois, have invented new and useful Coin-Receptacles, of which the following is a specification.

This invention relates to automatically registering coin receptacles particularly 10 adapted for use for registering fares in pre-payment street cars, or other passenger vehicles, and also for receiving and registering the admission fees in theaters and the like. It is likewise adaptable for use in connection with vending machines of various types.

An object of the invention is to provide a coin receptacle of the class described including audible and visible means for registering the deposit of the separate coins, and also a 20 permanent register indicating the totals of coins deposited in the receptacle.

Another object of the invention is to equip a coin receptacle of the class described with a coin receiving slot wherein the deposited 25 coins are held in view for inspection, with means for deflecting into a supplemental chute coins of a different character than those adapted to be received and registered by the device.

30 Another object of the invention is to equip a device of the class described with adjustable means for determining the number of coins to be held in the coin retaining slot, with provision for releasing coins from the slot automatically or manually.

Another object of the invention is to equip 35 a coin receptacle having coin registering means with a supplemental registering device for registering fares other than cash fares deposited in the receptacle.

In addition to the foregoing objects other valuable features and advantages attainable from the present invention will be recognized by those skilled in the art from the following detailed disclosure of a construction forming one embodiment of the invention, which is illustrated in the accompanying drawings in which—

Figure 1 is a front elevation of the coin 40 receptacle embodying the invention.

Fig. 2 is a rear elevation of the receptacle.

Fig. 3 is a front view of the receptacle having the front plate removed.

Fig. 4 is a rear view of the receptacle with 45 the back plate removed.

Fig. 5 is a cross section through the upper part of the receptacle taken substantially on the line 5—5 of Fig. 1.

Fig. 6 is an enlarged fragmentary view of certain parts of the coin registering mecha- 60 nism.

Fig. 7 is a vertical cross section through the same parts taken substantially on the line 7—7 of Fig. 6.

Fig. 8 is an enlarged detailed view of the 65 locking member for the coin gate.

Fig. 9 is an enlarged perspective view of the coin gate.

Fig. 10 is a perspective view of the locking 70 elements for the coin wheel.

Fig. 11 is a perspective detailed view of a form of bracket in which the coin gate and locking element for the coin wheel is sup- 75 ported.

Fig. 12 is a perspective view of a form of 80 spring for actuating the coin gate and locking member for the coin wheel.

Fig. 13 is an enlarged detail view of the 85 mechanism for supporting the coins in the coin slot and for automatically and manually releasing the same.

Fig. 14 is an elevation of the supplemental registering device.

Fig. 15 is a plan view of the same mecha- 90 nism.

Fig. 16 is a side elevation of the mecha- 95 nism.

In the embodiment of the invention illustrated in the drawings the case includes a metal frame 1 in which is supported a trans- 100 verse partition wall 2, which frame is fitted with a back plate 3 and a front plate 4. The bottom end of the back plate 3 is extended and curved under the bottom of the frame 1 forming a coin receiving compartment 5. 95 An opening 6 is cut in the up-turned wall of the extension permitting access of the hand for removal of the coin that drops into the compartment. The case is preferably formed from metal, the frame work being a cast 105 structure and the front and rear plates being of pressed sheet metal. In order to retain the parts of the case in assembled relation, the frame 1 is provided with ears or brackets 7, and tie rods 8 are extended through 110 perforations in the front and back plates, the rear end of the rods being provided with screw heads and the front ends being threaded to receive wing-nuts 9, thereby providing means for removably securing the 110

parts of the case in adjustment. The extended ends of the tie rods are perforated so that wire seals 10 may be placed through the perforations and sealed, so that it may be ascertained whether or not the case has been disassembled after adjustment.

The walls of the back plate are deflected inwardly as shown at 11 toward a longitudinal opening 12 in which may be fitted glass or other translucent material which is adjacent to a portion of the coin receiving slot, so that the coins in the slot may be viewed from the exterior of the case. The front plate 4 is equipped with a similarly formed deflection of the walls as shown at 13 and an opening 14, the opening 14 lying adjacent to the front face of the coin slot so that the coins in the slot may be viewed from the front of the case for inspection. In the upper portion of the front plate is formed a round opening 15 having a translucent closure 16 behind which is arranged the indicating dial of the registering mechanism. A coin hopper 17 extends upwardly from the top wall of the frame member 1, said hopper opening into a coin receiving chute 18. The chute 18 is formed from angle strips 19 and 20 which are supported against the rear face of the plate 2 adjacent to the opening from the hopper. The angle strips 19 and 20 are so disposed with respect to each other that the space between them is slightly in excess of the diameter of the coin for the reception of which the device is designed. Within the chute 18 is arranged a coin gate for controlling the admission of the coin into the coin registering mechanism and the coin retaining chute 21 into which the chute 18 opens. The coin gate between the chutes 18 and 21 comprises the elements illustrated perspectively in Fig. 9.

The coin gate includes a swinging member 22 which is pivoted on a rod 23 and operates through a vertical slot 24 formed in the plate 2 at the center of the back wall of the chute 18. The lower end of the member 22 has a downwardly inclined enlargement or shoulder 25. A horizontal plate 26 is connected with the member 22 and is adapted to operate in a horizontal slot 27 formed in the plate 2 and crossing the vertical slot 24. At one edge of the plate 26 is an upwardly turned lip 28 having its front edge inclined so that the forward edges of the shoulder 25 and the lip 28 are in substantially the same inclined planes. The front edge of the plate 26 at the base of the inclined edge of the shoulder 25 is inclined downwardly, so that when a coin is inserted in the chute 18 it rides against the front face of the shoulder 25 and of the lip 28 and over the edge of the plate 26. The pivot rod 23 on which the coin gate is mounted is supported in a bracket 37 secured to the plate 2. A spring

39 is secured to the plate 2 and is formed with an opening 40 through which the lower portion of the bracket 37 extends. The bracket 37 has an opening 41 therein through which a lug 42 on the plate 22 projects. The upper edge 43 of the spring 39 bears against the lug 42 and normally actuates the coin gate forwardly through the slots 24 and 27 constituting a closure across the chute 18.

A gate lock comprising a U-shaped member 30 pivoted at 31 on the plate 2 engages in a notch 32 in one end of the plate 26. The member 30 is designed to normally swing inwardly within the chute 18, the arm 80 thereof extending into the chute engaging in the slot 32 and holding the gate across the chute 18 preventing a coin from passing downwardly in the chute 18 until the member 30 has been swung outwardly and disengaged from the notch 32. When a coin of the diameter for which the machine is designed enters the chute 18 the weight of the coin operating against the arm of the member 30 extending into the chute, swings the arm laterally out of engagement with the notch 32, and the pressure of the coin on the bevel edge of the shoulder 25 and of the lip 28 causes the gate to swing outwardly, permitting the coin to move downwardly by gravity in the chute 18.

A supplemental chute for discharging coins of smaller diameter than will operate the lock for the gate is provided and comprises a run-way 33 having a discharge opening 34 at the exterior of the machine. The rear wall of the run-way 33 at the upper portion is the forward wall of the chute 18, so that when the coin gate remains locked the coin inserted in the chute 18 will be deflected over its forward wall and into the run-way 33 passing by gravity into the discharge opening 34, the inclined edges of the shoulder 25, the lip 28 and the plate 26 deflecting the coin in the supplemental chute or run-way.

When coins of the character designed to operate the gate lock are inserted in the chute 18 the gate will be operated as above described to release the coins into the bottom of the chute 18. At this point in the chute 18 is placed a locking device for the coin wheel. The coin wheel locking device comprises a swinging member including a vertically disposed plate 35 and a horizontally disposed plate 36, and is supported to swing in a bracket 37 of the same construction as the coin gate supporting bracket. As the support and actuating means for the coin gate and for the coin wheel locking device are the same it is unnecessary to repeat a description of the details thereof, suffice it to say that by means of the spring construction already described the locking member is normally actuated so that it pro-

jects into the chute 18 and the end of the plate 36 is thereby held so that it constitutes an abutment for the teeth of the coin wheel 44. The coin wheel 44 is mounted on a shaft, one end of which is journaled in a bracket 45 and the other end of which extends through the plate 2 and is entrained with the registering device. The coin wheel has formed in its periphery a plurality of notches 46 of semi-circular contour and of a diameter sufficient to accommodate the coins which the machine is designed to register.

Coins inserted in the chute 18 and passing below the coin gate swing the coin wheel locking device backwardly against the tendency of the spring 39 and enter the respective notches 46. The weight of the coin in the notch 46 rotates the coin wheel 44 one tooth, the movement of the coin wheel being arrested by the locking member swinging forwardly in its path after the coin has passed out of engagement therewith and into a recess in the coin wheel. The coin wheel shaft 47 is entrained with a mechanically operated adding and registering device 48 of known construction which operates to register the total of the coins passing through the device. Any suitable mechanical mechanism for coördinating the registering elements with the coin wheel may be employed, and it is unnecessary for the present purposes to describe in detail the construction of the registering element *per se*.

Upon the end of the shaft 47 of the coin wheel is an indicating pointer 49 which is adapted to coöperate with a scale 50. The purpose of the pointer 49 and the scale 50 is to indicate visually the deposit of the separate coins so that it may be observed whether each individual coin as it is placed in the box is properly registered.

After the coins have passed through the portion of the chute adjacent to the coin wheel and the coin wheel is operated to register the passage of the coin, it drops into the chute 21. The chute 21 is formed from a metal frame 51 attached to the plate 2, the front wall of the frame having cut out portions therein, and the portion of the plate 2 adjacent to the chute also being cut away so that a series of coins held in the chute 21 are in view through the openings in the front and back plates of the receptacle. The chute 21 opens into the receiving compartment or chamber at the bottom of the receptacle, but the passage of the coins from the chute 21 is controlled by a retaining mechanism which operates to discharge the series of coins from the chute 21 into the compartment or chamber at the bottom of the receptacle when a predetermined number have entered said chute 21.

The mechanism for supporting the coins in the chute 21 includes the swinging lever

52 pivoted at 53 and having a curved arm 54 which extends into the chute 21. The lever 52 has at its free end an adjustable weight 55 and is retained for operation against the face of the plate 2 by a guide strip 56. It will be observed that the weight 55 may be adjusted so that it will require predetermined numbers of coins to raise the lever to the dotted line position shown in Fig. 13. When the predetermined number of coins rests upon the curved extension 54 of the lever 52, the lever will move so that the curved extension is positioned out of the path of movement of the coins, and the coins will be discharged into the compartment or retainer at the bottom of the receptacle.

In order to operate the discharge mechanism manually there is provided a lever 57 which is pivoted at 58 and has an extension 59 which rests against the under side of an operating lever 60. The operating lever 60 is pivoted at one end at 61 and extends forwardly through the partition plate and terminates at the exterior of the receptacle in a thumb plate 62. The lever 57 has an extension 63 that constitutes an abutment for the end of the lever 52 holding it in proper position for supporting the coins in the chute 21. The lever 57 also has an upturned foot 64, the upper end of which bears against the lever 52. A retractile spring 65 normally retains the lever 57 in depressed position, but when the operating lever 60 is depressed at its forward end, the lever 57 is raised. The foot 64 engaging with the lever 52 raises said lever 52 so as to discharge the coins. The lever 57 is guided by a guide strip 66 supported on the plate 2.

Upon the plate 2 and at the side of the chute 21 is arranged a gong or bell 67. A spring clapper arm 68 is pivoted on the plate 2 at 69 carrying at one end the clapper or bell hammer 70 and extending at the other end into the chute 21. A pin 110 abutment 71 arrests the downward movement of the clapper arm. This arrangement provides audible means for indicating the number of coins passing through the chute 21, the separate coins depressing the clapper arm as they pass the extension that protrudes into the chute. Immediately after the coin has passed, the outer end of the clapper arm carrying the bell hammer descends, the spring action of the arm permitting the hammer to strike the gong and to rebound instantly, giving a clear audible indicating tone.

The receptacle is equipped with mechanism for registering fares or admission fees, other than those capable of being deposited in the registering mechanism, so that a record may be kept of transfers or the like on public conveyances, or passes and the like in theaters. This mechanism is illus-

trated in detail in Figs. 14 to 16 inclusive, and is incorporated in the receptacle. The mechanism referred to includes a register 72 of known construction comprising a series 5 of registering wheels and associated actuating and carrying mechanism. As the register *per se* is of a commercial type it is unnecessary to describe it in detail, suffice it to say that it is actuated from a ratchet and 10 pawl construction. The register is supported in a frame 73 on the inner face of the front plate of the register and is operated by a key lever 74 extending through the front plate so that it is accessible from the exterior of the receptacle. The key lever 74 15 has attached to its inner end a bar 75 which is connected to the pawl of the register mechanism. The bar 75 is normally drawn forward by a retractile spring 76, so that 20 when the key lever is pushed inwardly the pawl connected to the bar 75 is moved a sufficient distance to rotate the ratchet for operating the register a single space, the key lever and bar being returned to normal position upon release by the spring 76.

Coordinated with the register operating mechanism is provided means for sounding an audible signal to indicate each registration recorded by the register. This mechanism comprises a gong 77 supported on the back face of the front plate, which is sounded by a bell hammer 78 supported on a flexible bell hammer shank 79 secured at 80 to the back face of the front plate. The 30 means for operating the bell hammer includes a shoulder 81 on the rear end of the key lever 74 which operates a lever 82 pivoted at 83. The lever 82 is notched at 84, the shoulder 85 at the head of the notch constituting an abutment arresting the forward movement of the key lever. The lever 82 has an extension 86 at its front end which bears against the upper edge of an L-shaped lever 87 pivoted at 88. A retractile spring 89 40 tends normally to raise the short arm of the lever 87 and to retain it in the position best shown in Fig. 14, the long arm of the lever extending upwardly behind the gong adjacent to the bell hammer. Pivoted near 45 the extremity of the long arm of the lever 87 is a rocking lever member 90, the lever member 90 abutting against an abutment 91 formed on the lever. When the short arm of the lever 87 is depressed in opposition to 50 the spring 89, upon the inward movement of the key lever, the upper arm of the lever member 90 is raised in contact with a projection 92 from the side of the bell hammer 78, causing the bell hammer shank 79 to be 55 flexed or raised upwardly. After the end of the upper arm of the lever member 90 has moved beyond the projection 92, the bell hammer 78 by virtue of the flexible 60 character of the shank descends, sounding 65 the gong. When the key lever is released

the long arm of the lever 87 is free to descend, the lever member 90 rocking on its pivot to permit the upper arm thereof to clear the projection on the side of the bell hammer.

I am aware that numerous modifications may be made in the construction of the embodiment of the invention, and I do not limit myself therefore to the exact details shown and described, but what I claim and desire 75 to secure by Letters Patent, is:—

1. In a coin receptacle, a vertically arranged coin receiving chute, a coin discharge chute disposed at an angle to said receiving chute, a coin gate normally held by gravity 80 across the coin receiving chute, a detent engageable with the coin gate and adapted to lock the same in closed position, said lock device being operable by coins of a predetermined diameter to unlock the gate and 85 permit the passage of said coins from said receiving chute and unaffected by coins of smaller diameter, whereby said smaller coins are deflected to the discharge chute, a coin retaining chute for receiving coins from the 90 receiving chute that pass through the coin gate, a coin wheel having pockets in its periphery wherein coins pass from the receiving chute into the retaining chute and 95 whereby said coin wheel is rotated by gravity, and registering mechanism entrained with said coin wheel.

2. In a coin receptacle, a coin receiving chute, a discharge chute in communication with the receiving chute, and a coin retaining chute in communication with said receiving chute, a coin gate at the juncture of the receiving chute with the discharge chute and the retaining chute, comprising a pivoted element extending across the receiving 105 chute and adapted in closed position to deflect coins of one diameter into the discharge chute, a locking lever for holding the coin gate closed, said locking lever being operated by coins of a larger diameter to unlock the 110 gate permitting the same to move out of position across the receiving chute and to discharge said coins of larger diameter into the retaining chute, a coin wheel operated by the coins passing into the retaining chute, and registering mechanism entrained with 115 said coin wheel.

3. In a device of the character described, a coin chute for conducting coins to a place of delivery, a discharge chute diverging from the coin chute for discharging coins of a smaller size than those properly belonging in the coin chute, a pivoted element extending across the coin chute and arranged to divert into the discharge chute coins smaller than those properly belonging in the coin chute, a lock device for said element preventing operation of said element by said smaller coins and arranged to be released by coins 125 of the size which properly belong in the coin 130

chute, a coin wheel below the pivoted element extending into the coin chute and having pockets in the periphery thereof to receive the coins passing through the coin chute whereby said wheel will be operated by said coins, and mechanism entrained with said wheel for indicating the number of coins passing said wheel.

4. In a coin receptacle, a coin receiving chute, a coin retaining chute located below the receiving chute, and a discharge chute disposed at an angle to the receiving chute, a coin gate comprising a pivoted member extending across the receiving chute and normally held by gravity in closed position, a locking device engageable with the coin gate normally retaining the coin gate in closed position, whereby coins of a smaller diameter are deflected by the coin gate into the discharge chute, said locking device being controlled by coins of larger diameter whereby the gate is unlocked permitting the passage of said larger coins into the retaining chute, and a device extending into the retaining chute adapted to support the coins received therein, said device being operable by the weight of the coins in said retaining chute whereby the coins will be discharged from the retaining chute when a predetermined number have accumulated therein.

5. In a coin receptacle, a coin receiving chute, a coin retaining chute located below the receiving chute, and a discharge chute disposed at an angle to the receiving chute, a coin gate comprising a pivoted member extending across the receiving chute and normally held by gravity in closed position, a locking device engageable with the coin gate normally retaining the coin gate in closed position, whereby coins of a smaller diameter are deflected by the coin gate into the discharge chute, said locking device being controlled by coins of larger diameter whereby the gate is unlocked permitting the passage of said larger coins into the retaining chute, a device extending into the retaining chute adapted to support the coins received therein, said device being operable by the weight of the coins in said retaining chute whereby the coins will be discharged from the retaining chute when a predetermined number have accumulated therein, and a manually operated device for discharging the coins from the retaining chute.

55. 6. In a coin receptacle, the combination with a receiving chute and a retaining chute in connection therewith, of a coin wheel having a plurality of peripheral pockets extending into the path of movement of the coins from the receiving chute to the retaining chute, registering mechanism including a drive shaft whereon said coin wheel is mounted, a stop device for the coin wheel, said stop device being controlled by coins of a predetermined diameter, whereby the

coin wheel is unlocked from rotation when said coins of a predetermined diameter enter the receiving chute, and said stop device being unaffected by coins of a smaller diameter retaining the coin wheel against rotation except when coins corresponding to the diameter of the peripheral pockets are received in the receiving chute.

7. In a device of the character described, a coin chute arranged to conduct coins of a predetermined size to a place of delivery, a discharge chute diverting from the coin chute for receiving from the coin chute and discharging coins smaller than those properly belonging in the coin chute, an element extending across the coin chute and arranged to divert from the coin chute into the discharge chute the coins smaller than those properly belonging in the coin chute, and arranged to be operated by coins of the proper size to permit such coins to pass through the coin chute, a lock device for said element preventing operation of said element by said smaller coins and arranged to be released by coins properly belonging in the coin chute, and mechanism operated by the coins passing through the coin chute after said coins pass said element to indicate the number of coins which have passed said element.

8. In a coin receptacle, a vertical coin receiving chute, a device constituting a deflector for smaller coins, a coin gate for larger coins, a discharge chute for receiving the coins deflected by said device from said receiving chute, and a retaining chute for receiving the coins from said receiving chute passing through said coin gate, a lock device pivoted to swing into the receiving chute and controlled by the edgewise engagement of the coins of larger diameter unlocking the coin gate and permitting the coins to pass from the receiving chute to the retaining chute, a coin wheel the periphery of which extends below the receiving chute and having peripheral pockets for receiving the coins as they pass through said coin gate into the retaining chute, means operated with the movement of the coin gate for unlocking the coin wheel, permitting its rotation, and registering mechanism entrained with the coin wheel.

9. In a device of the character described, a coin chute, a discharge chute in communication with the coin chute for discharging coins of a smaller size than those properly belonging in the coin chute, a gate arranged to divert into the coin chute said smaller coins and to permit passage through the coin chute of coins of the proper size, a wheel below said gate arranged to be operated by the coins in the coin chute that have passed said gate, a lock for said wheel, connections for releasing said lock when said gate is operated by the passage of a coin therethrough,

6
and mechanism actuated by said wheel for registering the number of coins passing said wheel.

10. In a device of the character described, 5 a coin chute for conducting to a place of delivery coins of a predetermined size, a discharge chute diverging from the coin chute for discharging coins of sizes different from the size of coins properly belonging in the 10 coin chute, a device in the coin chute for diverting into the discharge chute coins of said different size and arranged to be operated by coins of the proper size to permit them to pass through said coin chute, a wheel 15 extending into the coin chute, and arranged to be operated successively by the coins passing through said coin chute, a lock device limiting extent of movement of said wheel by the respective coins passing through said 20 coin chute, and connections operable by the coins respectively passing said gate to release said lock device and permit said wheel to be operated.

11. In a device of the character described,

a coin chute for conducting to a place of 25 discharge coins of a proper size, means for diverting from said chute coins of a size different from the size of coins intended to pass through said chute, a wheel extending into the chute and arranged to be moved a 30 definite distance by each coin passing through the chute, a device for locking said wheel to prevent movement of said wheel beyond a predetermined extent of movement by any coin passing through the chute, mechanism actuated by said wheel for indicating the number of coins that have passed said wheel, and a signal device operated by the 35 coins that have passed said wheel to indicate the fact that the coins have passed the 40 wheel.

In witness whereof, I have signed this specification in the presence of two subscribing witnesses.

JOHN B. HUDDLE.
